[57] CLAIM

The ornamental design for a sole for a golf club head, as shown and described.

DESCRIPTION

FIG. 1 is a bottom perspective view of a sole for a golf club head embodying the design of the invention;

FIG. 2 is a bottom plan view of the sole for a golf club head of FIG. 1;

FIG. 3 is a rear elevational view of the sole for a golf club head of FIG. 1;

FIG. 4 is a right side view of the sole of a golf club head of FIG. 1;

FIG. 5 is a bottom perspective view of a second embodiment of the sole for a golf club head of FIG. 1;

FIG. 6 is a bottom plan view of the sole for a golf club head FIG. 5;

FIG. 7 is a rear elevational view of the sole for a golf club head of FIG. 5;

FIG. 8 is a right side view of the sole for a golf club head of FIG. 5;

FIG. 9 is a bottom perspective view of a third embodiment of the sole for a golf club head of FIG. 1;

FIG. 10 is a bottom plan view of the sole for a golf club head of FIG. 9;

FIG. 11 is a rear elevational view of the sole for a golf club head of FIG. 9; and,

FIG. 12 is a right side view of the sole for a golf club head of FIG. 9.

The broken line illustrations in the drawing figures are intended to illustrate the environment of the design sought to be patented and form no part of the design.
